UNITED STATES PATENT OFFICE.

WALTER W. OSWALD, OF SYRACUSE, NEW YORK.

ARTIFICIAL TOOTH.

1,211,749.

Specification of Letters Patent. Patented Jan. 9, 1917.

Application filed January 21, 1916. Serial No. 73,459.

To all whom it may concern:

Be it known that I, WALTER W. OSWALD, a citizen of the United States of America, and resident of Syracuse, in the county of 5 Onondaga, in the State of New York, have invented new and useful Improvements in Artificial Teeth, of which the following, taken in connection with the accompanying drawings, is a full, clear, and exact description.

This invention relates to certain improvements in artificial teeth, and refers more particularly to the means for attaching the porcelain bodies or facings of individual 15 teeth to the metal back-piece.

The main object is to provide a light, yet strong and durable interlocking connection between the main body and back-piece located so as to permit considerable portions 20 of the tooth to be cut or ground away in fitting without in any way interfering with any of the interlocking parts of such connection.

Another object is to permit the main body 25 and back-piece to be more easily and quickly secured to each other with greater assurance of proper securement than has heretofore been practiced.

A further object is to standardize attach- 30 ments of this character so that they may be used for all kinds of teeth.

Other objects and uses relating to specific parts of the device will be brought out in the following description.

35 In the drawings—Figure 1 is a front face view of a simple form of artificial tooth embodying my invention. Fig. 2 is an enlarged sectional view of the same tooth, taken on line 2—2, Fig. 1. Fig. 3 is a rear perspective view of the detached body of porcelain facing showing the form of the chamber therein for receiving the locking device for the rear plate. Fig. 4 is a perspective view 40 of the metal back-piece or plate showing the locking device for attaching it to the porcelain body. Fig. 5 is a front face view of a slightly modified form of artificial tooth. Fig. 6 is a sectional view of the same, taken on line 6—6, Fig. 5.

50 As illustrated, this artificial tooth comprises a main body or facing —1— of porcelain or other suitable material, a relatively thin sheet metal back-piece, preferably of

gold or other non-corrodible substance, and coöperative means, presently described, for 55 connecting the two parts together.

The main body is provided with a laterally elongated chamber —3— in the form of an inverted L in cross section and consists of a horizontal portion —4— open from the back of the main body and an upright or vertical portion —5— extending from the front of the horizontal portion —4— toward the crown of the tooth, but of considerably less depth from front to rear than 60 said horizontal portion so as to leave a considerable portion of the stock in the form of a flange —6— at the rear of the upright portion —5— of the chamber for a purpose hereinafter described. This chamber lies 70 wholly within the marginal edges and front face of the main body —1— and is centrally disposed therein with reference to the side edges, but is of considerably greater length from side to side than the vertical depth of 75 either the horizontal portion —4— or upright portion —5—, the vertical depth of the horizontal portion —4— being at least equal to and preferably greater than that of the upright portion —5—, which latter 80 is disposed at substantially right angles to the horizontal portion, the walls of the chamber being substantially flat and form right angles with each other.

85 The back-piece —2— is provided with a forwardly projecting angle plate which is also made in the form of an inverted L in cross section and is of approximately the same length laterally of the tooth as the chamber —3— in which it is adapted to fit, said angle 90 plate being preferably made of platinum or equivalent strong, but non-corrodible material, and consists of a substantially horizontal portion —7— and an upright portion —8— united at right angles to each 95 other, the rear edge of the horizontal portion being riveted or otherwise secured to the back-piece —2— so as to form a rigid unitary part thereof, and, in this instance, is provided with a recess —9— to allow the 100 retaining cement or filling, as —10—, to be worked therethrough for increasing the efficiency of securement of the two parts —1— and —2— to each other, it being understood that the back-piece —2— is flat 1 and substantially co-extensive in area with

the flat back of the main body —1— against which it is secured.

The horizontal portion —7— and upright portion —8— of the angle plate are comparatively thin and flat, the horizontal portion —7— being of substantially the same width from front to rear as the corresponding depth of the horizontal portion —4— of said chamber, while the upright portion —8— is of approximately the same or slightly less vertical depth than the corresponding depth of the horizontal portion of the chamber so as to allow it to be inserted into the open side of said chamber in assembling the two parts —1— and —2— together, it being understood that the thickness from front to rear of the upright portion —8— is slightly less than the corresponding depth of the upright portion —5— so as to allow it to readily enter therein as the parts —1— and —2— are moved lengthwise relatively to each other in the act of attaching them one to the other.

As shown more clearly in Fig. 4 and by dotted lines in Fig. 2, the opposite ends of the horizontal portion or ledge —7— of the angle plate are provided with braces —11— having their rear edges riveted or otherwise secured to the back-piece —2— to additionally support the angle plate against excessive strains, and also to provide additional area for contact with the cementitious filling —10— when the parts —1— and —2— are assembled. In like manner and for a similar purpose, the opposite ends of the upright portion or flange —8— of the angle plate are connected to the corresponding ends of the horizontal ledge —7— by braces —12— shown in Fig. 4 and by dotted lines in Fig. 2. When these braces are employed the main body —1— of the tooth is provided with corresponding channels —13— communicating with the horizontal portion —4— of said chamber to permit the insertion of the angle plate into the chamber.

In Figs. 5 and 6, I have shown a slightly modified form of main body —1'— and back-piece —2'— in which those parts are provided with rearwardly extending offsets —14— and —15— having their contiguous faces disposed in approximately the same horizontal plane as the lower wall of the horizontal portion —4— of the chamber —3—, but otherwise the chamber and angle plate are substantially the same as that previously described.

In assembling the parts —1— and —2—, a suitable quantity of soft cementitious material, capable of hardening after the parts are assembled, is placed in the chamber —3—, whereupon the back-piece —2— with the angle plate thereon is brought into position to register the upright portion —8— of the angle plate with the open side of the horizontal portion —4— of the chamber

—3—, and the two parts —1— and —2— are then pressed together to force the angle plate into the soft cementitious material —10— until the upright portion —8— is registered with the upright portion —5— of the chamber —3—. The two parts —1— and —2— are then moved lengthwise of each other in reverse directions to cause the upright portion —8— to enter the chambered portion —5— as far as possible, or until limited by the close juxtaposition of the horizontal ledge —7— and adjacent face of the flange —6—. This operation is quickly performed and it is all that is necessary to properly secure the two parts —1— and —2— to each other, the completed tooth being then laid aside to allow of the soft cementitious material —10— to set or harden, after which the tooth is ready for mounting.

The angle plate consisting of the horizontal ledge —7— and vertical flange —8—, together with the end braces —11— and —12— and back-piece —2—, constitutes a box-like structure fitting over and upon the flange —6— of the main body —1— and provides an exceptionally light, strong and durable connection between the parts —1— and —2—, and at the same time permitting said connection to be brought wholly within the marginal edges of the tooth, leaving a considerable body between it and the crown for grinding, cutting and fitting without in any way interfering with the connection.

What I claim is:

1. An artificial tooth comprising a main body of porcelain or equivalent material having a laterally elongated chamber of angular cross section from front to rear opening from the back, and a metal back-piece having a forwardly projecting shelf-like angle plate seated in said chamber for locking the two parts together, and a cementitious filling in the chamber for holding the angle plate in the chamber.

2. An artificial tooth comprising a main body having a laterally elongated chamber consisting of a horizontal portion extending from the back forwardly and an upright portion extending from the inner end of the horizontal portion toward the crown of the tooth, and a metal back-piece having a laterally elongated angle plate consisting of a substantially flat horizontal portion seated in the horizontal portion of the chamber and a flat upright flange projecting downwardly from the inner edge of the horizontal portion and seated in the upright portion of the chamber.

3. An artificial tooth comprising a main body having a laterally elongated chamber consisting of a horizontal portion extending from the back forwardly and an upright portion extending from the inner end of the horizontal portion toward the crown of the tooth, a metal back-piece having a laterally

elongated angle plate consisting of a substantially horizontal portion seated in the horizontal portion of the chamber and an upright portion seated in the upright portion of the chamber, and end braces connecting opposite ends of the upright portion with corresponding ends of the horizontal portion of the angle plate.

In witness whereof I have hereunto set my hand this 19th day of January, 1916. 10

WALTER W. OSWALD.
